[57] CLAIM

The ornamental design for a pathological waste incinerator for farm use, as shown and described.

DESCRIPTION

FIG. 1 is a front elevational view of a pathological waste incinerator for farm use, showing my new design; FIG. 2 is a side elevational view thereof, viewed from the left of FIG. 1, with the burner removed to reveal the appearance of the underlying surface portions of the incinerator;

FIG. 3 is a side elevational view thereof, viewed from the right of FIG. 1;

FIG. 4 is a top plan view thereof; and,

FIG. 5 is a rear view thereof.

The bottom is plain.

FIG. 1

FIG. 2

FIG. 3

FIG. 5

FIG. 4
